(57) **CLAIM**

The ornamental design for a drink preparing machine, as shown and described.

DESCRIPTION

FIG. 1 is a front, right and top side perspective view of a drink preparing machine showing our new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the portion marked '9' in FIG. 2;

FIG. 10 is a view showing the screen in a rotated state; and, FIG. 11 is another view showing the screen in a rotated state. The broken lines shown in the drawings represent portions of the drink preparing machine that form no part of the claimed design.

The dot-dashed broken lines indicate cutoff boundaries for the enlarged detailed portion views and form no part of the claimed design.
